John C. Dillingham.

UNITED STATES PATENT OFFICE.

HENRY LA ROE, OF NORTH RIVER, NEW YORK.

BED-SPRING TIGHTENER.

1,273,074.

Specification of Letters Patent. Patented July 16, 1918.

Application filed October 20, 1916. Serial No. 126,667.

To all whom it may concern:

Be it known that I, HENRY LA ROE, a citizen of the United States, residing at North River, county of Warren, and State of New York, have invented certain new and useful Improvements in Bed-Spring Tighteners, of which the following is a specification.

This invention has relation to apparatus for tightening woven wire structures such as bed springs, fence-wire and the like. And has for its general object when used as a bed spring tightener to facilitate the tightening of such spring, without requiring that the tightener be detached from the bed or adjusted relatively to the spring. And to this end the invention resides in a clamp adapted to engage the bed spring and extend transversely thereof, and devices for connecting the clamp to a suitable portion of the bed spring frame and adapted for adjusting the clamp bodily in one direction so as to exert a pull on the spring.

Other objects will appear and be better understood from that embodiment of my invention of which the following is a specification, reference being had to the accompanying drawings forming part hereof, and in which:

Figure 1, is a plan view of the invention in use.

Fig. 2, is a detail fragmentary front elevation of the invention.

Fig. 3, is a detail cross sectional view of the device looking at right angles to Fig. 2.

Fig. 4, is a fragmentary perspective of a modified form of jaw.

Fig. 5, is a detail front elevation showing the invention in use as a wire stretcher.

5 indicates the bed spring one end of which is secured to one end of the bed spring frame 6. The devices for fastening the opposite end of the said spring to the other end of the frame are eliminated and the said opposite or free end of the said spring is disposed between the jaws 7 and 8 of a clamp "a" which as shown extends transversely of the spring 5. As shown the jaws 7 and 8 are held in frictional contact with the opposite faces of the intervening portion 10 of the spring 5 by a plurality of clamp screws 9 which pass through threaded metallic bushings 10 carried by the jaws 7 and 8, and through the meshes of the spring 5. The screws 9 have their upper ends provided with laterally extending handles 9' so that the turning of the screws can be conveniently

effected. The portion of the spring 5 which projects beyond the clamp "a" is engaged by a holding device which may be in the form of a serrated plate 11, or a plurality of 60 angular shaped pins 12. In either event the holding device will be arranged on the outer side of one of the jaws as for instance the jaw 7, and the serrations or the ends of the downwardly extending side portions of the 65 pins 12 will project beyond the inner face of the jaw 7 for such distances as will permit the said serrations or the end portions of the pins to pass through the meshes of the spring 5 when the jaws are adjusted to bear on the 70 opposite faces of the spring as shown. Obviously with this construction the free end portion of the spring can be held from slipping between the jaws when a pull in one direction is exerted on the clamp "a".

When the clamp is attached to the spring as shown the opposite ends of the clamp project for appreciable distances beyond the opposite sides of the spring and in these projecting end portions transversely disposed oblong openings 13 are formed and disposed in one of the jaws for instance the jaw 8. Adjusting screws 14 and 15 pass loosely through the openings 13 and nuts 16 which are prevented from turning in unison with the screws by suitable devices as for instance lugs 17 attached to the upper jaw 7 and constructed and arranged so as to bear on one face of the nuts. The adjusting screws also pass through angular 80 shaped engaging members or hooks 18-18 which are constructed so as to engage the ends of the side rails of the bed spring frame 6, and interlock with these. The outer ends of the screws 14 and 15 terminate 85 in crank handles 19-19 and longitudinal movement of the screws through the engaging devices or hooks 18-18 is prevented by enlargements 20 formed with or otherwise suitably secured to the screws 14 and 15. 90 These enlargements are circular in contour and are disposed in correspondingly shaped sockets 21 in the hooks 18, and outward movement of the heads from the sockets is prevented by plates 22 which form closures 100 for the open ends of the sockets and have openings in which screws 14 and 15 are free to rotate.

In using the tightener of this invention the clamp "a" is applied as shown in the 110 drawings to one end portion of the spring prior to detaching that end from the frame

6. In the act of positioning the clamp the hooks or engaging devices 18 are adjusted onto the ends of the side rails of the frame 6, after which the handles 19—19 are turned 5 so as to cause opposite pulls on the spring 5 and hooks 18 sufficient to cause the latter to bind on the side rails of the frame 6. The operator now disengages that end of the spring which is nearest to the clamp "a" 10 from the end of the frame 6, after which the handles 19 are turned in the direction necessary to enable the screws coöperating with the nuts 16 to advance or move the clamp "a" bodily toward the hooks 18. This 15 movement on the part of the clamp for a required distance has the effect of tensioning the spring 5 to the required degree. In the act of tightening the spring it will be noted that the free end thereof is held 20 against displacement by spring holding devices 11 and 12 and not solely by the binding action of the jaws 7 and 8, so that the relatively small amount of pressure exerted by these jaws on the spring will not operate 25 to distort or damage the spring fabric. It will be further noted that the provision of the oblong openings 13 permits of operating the crank handles 19 one at a time or each independently of the other in that these 30 openings permit of an appreciable amount of lateral movement of the clamp with respect to the spring and independently of the screws 14 and 15.

35 After the spring has been tightened the clamp "a" can be left in operative position on the spring frame, or if desired the clamp may be removed from the frame. In the latter case that end bar adjacent the clamp will have to be removed previous to the 40 stretching of the spring, and replaced and

attached to the spring after the latter has been tightened, so as to hold the spring at the proper tension when the clamp "a" has been removed.

When the device is used as a fence wire 45 stretcher the elements 14, 15, 16, and 18 may be eliminated prior to securing one end of the woven wire 20 between the jaws 7 and 8 as shown. When the wire is so secured the ends of a chain 21 are attached to the 50 opposite end portions of the clamp "a" so that when a block and tackle such as is indicated at 22 is engaged with the middle portion of the chain 21 the woven wire 20 may be stretched between the posts 23 in the ordinary manner. 55

What is claimed as new is:

In a bed spring tightener a clamp including a pair of jaws and clamp screws passing through said jaws, one of said jaws having 60 formed therein oblong openings and hollow movable screw threaded elements in alignment with said openings, the other of said jaws having means adapted to prevent rotation of said threaded elements and to allow of their adjustment along said oblong openings, a pair of hooks adapted for connection to one end of a bed spring frame and provided with transverse openings, and adjusting screws rotatably mounted in the 65 openings of the jaw and hooks and screwed into the said screw threaded elements. 70

In testimony whereof, I have signed my name to this specification in the presence of two subscribing witnesses, this 18th day of Sept. 1916. 75

HENRY LA ROE.
